United States Patent Office.

PETER LOW, OF CLEVELAND, OHIO.

Design No. 4,183, dated June 28, 1870.

DESIGN FOR A COOKING-STOVE.

The Schedule referred to in these Letters Patent and making part of the same

To all whom it may concern:

Be it known that I, PETER LOW, of Cleveland, in the county of Cuyahoga and State of Ohio, have invented a certain new Design for Stoves; and I do hereby declare that the following is a full, clear, and exact description thereof, reference being had to the accompanying drawings and to the letters of reference marked thereon which form a part of this specification.

The nature of my design is fully represented in the accompanying photographic illustration of the same, to which reference is made.

Claim.

I claim as my invention—
The design for stove, as shown.

In testimony that I claim the foregoing as my own, I affix my signature in presence of two witnesses.

Witnesses:

FREDK. A. BRAND,
ANTON DREKER.
